[57] CLAIM

The ornamental design for video display control or similar article, as shown and described.

DESCRIPTION

FIG. 1 is a front elevational view of a video display control or similar article showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a perspective view thereof; and,
FIG. 8 is a perspective view of a second embodiment of the design shown in FIG. 1 wherein the only difference resides in the appearance of the control panel.

FIG. 1

FIG. 2

FIG. 3

FIG. 4

FIG. 5

FIG. 6

FIG. 7

FIG. 8
